UNITED STATES PATENT OFFICE.

ALLEN LOOMIS, OF TOLEDO, OHIO, ASSIGNOR TO THE WILLYS-OVERLAND COMPANY,
OF TOLEDO, OHIO, A CORPORATION OF OHIO.

TOP SUPPORT.

Application filed September 10, 1919. Serial No. 323,001.

To all whom it may concern:

Be it known that I, ALLEN LOOMIS, residing at Toledo, county of Lucas, State of Ohio, have invented certain new and useful

5 Improvements in Top Supports, of which I declare the following to be a full, clear, and exact description.

This invention relates to improvement in top supports, more particularly to a form of

10 top support adapted to be applied to a vehicle having a folded top.

One object of the invention is to provide a device of this character wherein the top support is of simple construction and efficient in

15 operation.

A further object of the invention is to provide a top support capable of supporting a top a sufficient distance rearwardly of the body to accommodate a plurality of spare

20 tires located adjacent the rear of the body.

A further object of the invention is to provide a device of this character constructed in such a manner as to permit the folding top to be pivoted to the body of the vehicle at a

25 point near the rear end thereof.

A further object of the invention is to provide a device of this character which is constructed so as to be capable of supporting the top in two positions of adjustment.

30 A further object of the invention is to provide an improved device of this character, the parts of which are capable of being retained in folded position when not in use.

Further objects of the invention relate to

35 economies of manufacture and details of construction as will hereinafter appear from the detailed description to follow.

The objects of the invention are accomplished in one instance by the devices and

40 means described in the following specification, but it is evident that the same may be varied widely without departing from the scope of the invention as pointed out in the appended claims. A structure constituting

45 one embodiment of the invention is illustrated in the accompanying drawings forming a part hereof in which:

Figure I is a rear end elevational view of an automobile provided with the improved

50 top support, a portion of the top being broken away along the line I--I of Figure II to illustrate the position of the parts when the supporting member is in operative position for supporting the top.

Figure II is a side elevational view of the 55 rear end portion of an automobile, illustrating the position of the supporting member when supporting the top is one of its adjusted positions.

Figure III is a detail rear elevation of the 60 top supporting mechanism when the parts are retained in folded position.

Figure IV is a side elevational view of the rear end portion of an automobile illustrating the position of the top supporting 65 member when supporting the top in the uppermost of its two adjusted positions.

In the use of automobile bodies of the 70 sport type which are comparatively low relatively to the older models, it is desirable to pivot the folding top of the vehicle at a point near the rear end portion of the body in order to permit the top when in folded position to extend to the rear of the body a sufficient distance not to interfere with the 75 spare wheels ordinarily supported at the rear end portion of the automobile. Under these circumstances it is inadvisable to employ the usual form of top supporting

brackets secured to the body of the vehicle, 80 and it is therefore necessary to provide other suitable supporting means for retaining the folded top in proper position and supporting the same when folded.

It has also been found to be desirable, especially when wheel 85 carrying devices of the type illustrated here-with are employed, to provide means for supporting the top temporarily in a position raised above its usual and ordinary folded position. Moreover, when the form of wheel

carrying mechanism illustrated in the accompanying drawings is employed, the position of the wheels is such as to make it highly desirable to pivot the folding top 90 farther towards the rear of the vehicle body 95 than is ordinarily done in order to provide sufficient room for the spare wheels, and enable the same to be supported without serious interference with the folded top. In view of the necessity for thus pivoting the folded top at a point adjacent the rear end portion

100 of the vehicle body, and providing means for retaining the same in two positions of adjustment the present improved form of 105 supporting mechanism is provided wherein the desirable features above enumerated are obtained, and at the same time the supporting mechanism is constructed to enable the

same to be suitably folded so that it will not interfere with the remaining parts of the vehicle structure when the top is raised.

In the embodiment of the invention illustrated herewith, 1 indicates the body portion of the automobile supported by the usual ground engaging wheels 2, the automobile structure comprising a frame portion including a pair of rearwardly extending side frame members 3 which are connected to each other near the rear end portion of the vehicle body by means of a transverse brace member 4 and a transversely extending cross rod 5. A folding top 6 of the usual construction is pivoted to the vehicle body at a point adjacent the rear end portion thereof as indicated at 7, said top being provided with the usual supporting bows 8 which are adapted to support the same and retain it in proper extended position. Pivotally mounted upon the cross rod 5 is a tire carrier 10 which is constructed so as to pivot about the rod 5 as a center, and be capable of being retained in upright position as illustrated in full lines in Figure IV, or to be swung about the rod 5 as a center into an inclined ground engaging position, the carrier being illustrated in the course of being swung into ground engaging position in dotted lines in Figure IV. The tire carrier comprises a pair of oppositely extending tapered members 11, upon which spare wheels 12 are capable of being releasably secured when the carrier is in its normal upright position. It will be seen upon reference to the drawings that when spare wheels are in position upon the tire carrier and the tire carrier is retained in its normal upright position, the upper portions of the spare wheels are located adjacent the rear end portion of the vehicle body and at a sufficient height to interfere with the folding top if the same is mounted upon the vehicle body and held by the usual bow supports secured to the rear end portion of the body. In order to suitably accommodate the folding top to the spare wheels adapted to be supported by the carrier, it has been found to be advisable to pivot the folding top at a point somewhat nearer the rear end portion of the vehicle body than is usual in the ordinary constructions, and provide suitably independent means for supporting the folded top in its folded position.

The top supporting mechanism comprises a pair of pivotally mounted standards 14, each of which is pivoted at 16 to a bearing 15 firmly secured to the cross rod 5 at points adjacent to and spaced outwardly from the points from which the carrier structure previously described is pivotally mounted. The standards 14 are pivoted to the bearings 15 carried by the cross rod so as to be capable of free movement in a traverse vertical plane and adapted to be supported in folded position by means of brackets 17 which extend outwardly from and are carried by the outwardly extending portions of the carrier supporting frame. Each of the brackets 17 are provided with a pair of forked arms 18 which partially embrace and support the standards when the standards are in their folded position. Pivoted as at 19 to the upper end portion of each standard is a bow support 20, each of the bow supports being pivoted to the upper end portions of the standards so as to be capable of movement to a certain limited extent about the upper end portion of the standard, but a stop (not shown) is provided for preventing excessive movement of each bow support about its standard in a direction outwardly thereof from the position of the top as illustrated in Figure I of the drawings. Each bow support comprises a main portion 21 to which is pivotally connected as at 22, a member 23 provided with projections 24 extending inwardly therefrom for fitting between the spaces between the bows when the bows are held in position between the members 21 and 23. A link 25 is pivotally secured to the main portion 21 of the top support near the end thereof and is adapted to extend over the end portion of the member 23 whereby the member 23 may be locked into position adjacent the member 21 by means of a suitable form of cam lever 26. It will be understood from the preceding description that the standards and bow supporting members are capable of taking up the position illustrated in Figures I and II of the drawings, wherein the bow supporting members are positioned in their outward limits of movement with respect to the upright standards, and the bows for supporting the top are positioned within and firmly held between the members 21 and 22 for supporting the top in its normal folded position.

When it is desired to raise the top into the position illustrated in Figure IV for the purpose of permitting the spare wheel carrier to be readily swung upon its pivots to permit removal of one of the spare wheels, the bows are released from engagement by the members 21 and 23, and the top raised into the position illustrated in Figure IV, whereupon the members 21 and 23 are again attached together by means of the link 25 and cam lever 26 whereupon the lowermost of the top supporting bows may be allowed to rest within and be supported by the slot 27 formed between the upwardly projecting end portions of the members 21 and 23. It will be seen that the top is capable of being firmly supported in this raised position while one or more of the spare wheels is removed from the carrier, and after said wheels have been removed or replaced, the top may again be lowered into

the position illustrated in Figures I and II, and the bows secured between the parts of the bow supports.

When the vehicle top is in its raised position it is desirable to provide means for retaining the bow supporting members in folded position where they will be free from interference with the remaining portions of the vehicle structure. When the top is 5 in its raised position, the standards 14 are permitted to swing about their pivot points 16 until they engage with the forked arms 18 carried by the brackets 17 and occupy the position illustrated in Figure III of 10 the drawings. When the standards are thus folded, the bow supporting members are preferably swung about the standards into the position illustrated in Figure III where they lie against the inner surfaces of the 15 standards, and are protected against injury. When the parts are in this folded position they may be suitably retained therein by means of straps 29 passed about the standards 14 and the adjacent supporting members for supporting the tire carrier. A pair of detachable flexible members 30 are provided for the purpose of 20 limiting the outward movement of the standards 14 and each of these flexible members is preferably formed of a small chain provided with a leather or canvas covering 25 to prevent marring of the finish upon the frame, each of these flexible members being provided with hooks 31 at opposite ends 30 thereof which may be fixedly or releasably positioned within suitable openings or loops formed upon the standards 14 and the tire carrier respectively. It will be readily understood that these flexible members limit 35 the outward movement of the standards 14 whereupon the standards are incapable of being ordinarily swung outwardly beyond the position illustrated in Figure I of the drawings, in which position they are suitably placed for supporting the bows of the 40 folding top.

It will thus be seen that ready and efficient means are provided for suitably supporting the top in either of two positions of adjustment, whereby the same may be retained in its normally lowered position and held against movement therein or retained in a partially raised position to facilitate the removal or replacement of the 45 spare wheels. Whenever the top is in its raised position, the supporting members above described may be folded into such position as to be out of the way and positioned in such a manner as to be unlikely 50 to become injured. It will be noted that the top supporting mechanism is positioned in

a plane intermediate of the transverse planes occupied by the spare wheels 12 whereupon the supporting mechanism in its folded position lies between the spare wheels and 55 therefore entirely out of the way.

While I have shown and described in considerable detail a specific embodiment of my invention, it is to be understood that this showing and description is illustrative 70 only and for the purpose of rendering my invention more clear.

What I claim as new and desire to secure by Letters Patent is:—

1. In a device of the character described, 75 a vehicle having a folding top, a body and a frame, top supporting standards pivoted to said frame to swing behind said body transversely thereof and means for limiting the outward movement of said standards. 80

2. In a device of the character described, 85 a vehicle having a folding top, a body and a frame extending rearwardly thereof, standards pivoted to said frame to swing transversely behind said body, means limiting the inward and the outward movement of said standards and bow supports pivoted to the outer ends of said standards. 90

3. In a device of the character described, 95 a vehicle having a folding top, a body and a frame extending rearwardly thereof, standards pivoted to said frame to swing transversely behind said body, brackets for supporting said standards when swung inwardly, flexible members for limiting the outward movement of said standards, bow supports pivoted to the outer ends of said standards whereby they may be folded there against when the standards are swung inwardly into inoperative position. 100

4. In a vehicle provided with a folding top, a frame including a cross bar, standards pivotally mounted on opposite ends of said cross bar, top supports pivotally 105 mounted on the ends of the standards, said top supports being adapted to be moved away from each other in the same plane to a predetermined position to engage the top. 110

5. In a vehicle provided with a folding 115 top, a frame including a cross bar, standards pivotally mounted on opposite ends of the cross bar, top supports pivotally mounted on ends of the standards, said top supports being adapted to be moved toward or away from each other in the same plane when the standards are in operative position.

In testimony whereof, I affix my signature.

ALLEN LOOMIS.
